WILLIAM J. RYAN, OF LOS ANGELES, CALIFORNIA, ASSIGNOR TO THE TEXAS COMPANY,
OF NEW YORK, N. Y., A CORPORATION OF DELAWARE

HEAT EXCHANGER

Application filed December 2, 1930. Serial No. 499,503.

This invention relates to heating devices of the kind that are used for causing a heated substance flowing thru one conduit to give up its heat to a continuously changing body of fluent substance moving thru a juxtaposed conduit, and refers more particularly to an apparatus comprising an element having a plurality of longitudinal passageways and a plurality of adjacent transverse passageways arranged in alternate relation and disposed so as to effect an interchange of heat between a continuously changing body of liquid or gas flowing thru the longitudinal passageways and a continuously changing body of liquid or gas which is being drawn or forced thru the transverse passageways in a direction generally counter current to the other body.

The principal object of the invention in its broadest aspect is to provide simple and efficient means for causing hot vapors which escape from an evaporating tank to give up their heat to a body of relatively cool liquid which is being drawn or forced thru a conduit to a heating zone.

In a specific application the invention provides novel apparatus particularly adapted to accomplish the double purpose of condensing certain portions of a petroleum vapor and heating a relatively cool fluid by passing the two substances in heat interchange with each other. In the pyrogenous conversion of relatively heavy hydrocarbon oils, it is ordinarily desirable to employ fractionating or dephlegmating apparatus, in combination with the cracking means, for condensing and separating certain of the higher boiling fractions evolved during the processing. These condensates may be discharged then from the system or they may be returned to the cracking or vaporizing equipment for further treatment. It is not uncommon, for example, to use for this purpose a fractionating or dephlegmating tower provided with suitable packing of the order of bubble trays and caps, rocks, chains, or other baffling or restricting means, which has openings and flow lines as necessary for its proper operation.

Vapors from the still enter such a tower

at a suitable point, which may be near the bottom, and are permitted to bubble up thru the tower in open relation with the packing and refluxing condensate which is formed by part of the vapors being condensed due to heat losses to the packing material and the wall of the tower. This condensate is separated and trapped out thru openings at the bottom or at other points in the tower, and the remaining vapors eventually emerge thru an opening near the top of the tower and are disposed of in some favored manner. It is sometimes of advantage to introduce into the upper portion of a dephlegmating or fractionating tower of this type, a certain amount of relatively cool oil to assist in removing by condensation the undesirable heavier constituents of the vapor which have escaped condensation in the lower portion of the tower.

It is of particular importance, with reference to this class of equipment, to provide means for separating rapidly and efficiently the lower boiling products having desired characteristics from all higher boiling products of distillation. To allow the heavier products of distillation to be entrained along with the lighter ones and to be carried overhead mechanically, would obviously defeat the very purpose of the installation. It would result in contamination of the lower boiling distillates having desired characteristics, with higher boiling ones having objectionable qualities. On the other hand, to allow the lighter fractions to be trapped out and recycled thru the system, would result of course in decreased efficiency, with corresponding low production and high fuel and operating costs.

With most of the equipment now in use, difficulty is experienced in securing clean separation of distillates. Ordinarily the rapid flow of vapors thru a dephlegmating or fractionating tower is such that separation is difficult to control, with the result that certain of the condensate is carried over mechanically by sheer velocity of the vapors. This tendency is augmented at times by relatively close spacing of the individual units which compose the packing element em-

ployed in such apparatus, which increases the facility with which liquids may be carried mechanically from one elevation to another within the tower. On the other hand, 5 certain of the lighter fractions may be condensed along with the heavier ones and withdrawn from the system or returned to cracking or vaporizing equipment for further treatment.

10 My invention contemplates the use of apparatus peculiarly adapted to the purpose at hand by means of which a condensation and separation of the higher boiling fractions will be rapid and complete and one 15 which will also bring about a continuous redistillation of the lighter fractions which might have been unintentionally precipitated with the heavier ones before these reach the trapping out means.

20 The economy of my invention both as regards installation and operating costs will be apparent to those skilled in the art.

25 The accompanying drawings, which are to be considered in connection with the following description, illustrate a preferred embodiment of my invention, but are not to be understood as imposing any limitations on the spirit and scope of my invention which is defined in the appended claims.

30 In the drawings:

Fig. I is a sectional view in plan of a heat interchange unit constructed according to the invention, taken on the line I—I of Fig. II.

35 Fig. II is a sectional view in elevation taken on the line II—II of Fig. I.

Fig. III is a sectional view in elevation taken on the line III—III of Fig. I.

40 Fig. IV is a fragmentary view of a baffle plate showing staggered arrangement of perforations before corrugating the plate.

45 Fig. V is a diagrammatic illustration of a plurality of slightly modified heat interchange units arranged in series indicating the transversely arranged paths of the substances passed there thru.

Fig. VI is a sectional view taken on the line VI—VI of Fig. V.

50 Fig. VII is a sectional view taken on the line VII—VII of Fig. V.

55 Referring now to Figs. I, II, III, IV, of the drawings, a casing is composed of a shell 1 and end cover members 1a and 1b having an oil inlet 2 and an oil outlet 3, and a vapor inlet 4 and a vapor outlet 5. Arranged with- 60 in the casing and communicating with the oil inlet 2 and the oil outlet 3, is a plurality of longitudinal slot-like oil passageways 6, 7, 8, 9, separated by partitions 10, 11, 12. The partitions are situated so as to alternate 65 the direction of flow of the oil thru the longitudinal slot-like oil passageways 6, 7, 8, 9, and to effect a general counterflow relation with the vapors thru adjacent alternately disposed transverse passageways 13. A corrugated 70 baffle 14 containing staggered rectangular

perforations is placed in each of the passage-ways 13 all of which communicate with the vapor inlet 4 and the vapor outlet 5. The assembly of metal plates forming the oil passageways 6, 7, 8, 9, and the adjacent alternately disposed vapor passageways 13, is se- 75 curely mounted on a pair of tube or passage-way sheets 16, 17, and these in turn are se- curely fastened inside the casing. A pair of valved condensate drain pipes 18 and 19 are 75 provided for draining off such condensate as may be precipitated from the vapor in this zone.

In operation, relatively cool oil supplied from storage not shown is admitted at the 80 point 2 and passed successively thru the longitudinal slot-like passageways 6, 7, 8, 9, in heat exchange relation with vapors produced in communicating cracking or vaporizing apparatus not shown, which are introduced into the casing at the inlet 4 and passed thru the adjacent alternately disposed transverse va- 85 por passageways, 13 and discharged at the outlet 5. The flow of oil thru the system not only is at right angles to the flow of vapors, but the direction of the oil, entering at the point 2, moved down thru the longitudinal passageways 6, up thru the passageways 7, down again thru the passageways 8, and up thru the passageways 9, then discharged at the point 3 is generally counter current to the flow of vapors thru the adjacent alternately disposed transverse vapor passageways 13.

90 Partial condensation of the vapors is ac- 95 complished by the heat interchange with the relatively cool oil, and separation of the heavier precipitating condensate is aided by the rapid change of direction thru the staggered perforations in the corrugated baffle plates 14 and by the contact and coalescing of the liquid particles thereon. The condensate thus gathering flows down over the baffle plates 14 under continuous exposure to the warm vapors passing thru and the unintentionally entrained lighter vapor is according- 100 ly subjected to continuous redistillation, while the remaining heavier condensate is trapped out thru the valved outlets 18, 19, to be returned to cracking or vaporizing equipment or otherwise disposed of. In this novel and 110 effective manner substantially all of the heat withdrawn from the entering hot vapors is transferred directly to relatively cool oil, which may then be further heated as neces- 115 sary and ultimately charged to cracking or vaporizing equipment.

120 Referring now to Figs. V, VI, VII, of the drawings, a plurality of small single pass units 20, 21, 22, are arranged in series, prefer- 125 ably superposed. A vapor line is arranged to conduct vapors from cracking or vaporizing equipment not shown into an inlet 23 of the units 20, 21, 22, which are appropriately connected in this sequence for vapor com- 130 munication, and an outlet 24 is connected to

a disposal line not shown. An oil line is arranged to deliver a stream of relatively cool oil from a source of supply not shown into an inlet 25 of the units 22, 21, 20, which are 5 appropriately connected in this sequence for oil communication, and an outlet pipe 26 is connected to a disposal pipe not shown. Arranged within each of the elements 20, 21, 22, and communicating with the respective oil in- 10 lets and outlets, is a plurality of longitudinal parallel slot-like oil passageways 30. Alternately disposed adjacent each of the longitudinal slot-like oil passageways 30 and communicating with the respective vapor in- 15 lets and outlets, is a plurality of transverse vapor passageways 31 having corrugated baffles 32 containing rectangular staggered perforations. In general the assembly of these individual units resembles that of Figs. 20 I, II, and III, with the exceptions, that the flow of the liquid or cool oil is downward and unbroken and the oil is forced into and out of the units thru single openings and a condensate is withdrawn from the vapor section 25 of each unit. The general counter flow movement of the substances undergoing heat interchange is accomplished by superposing the units rather than situating a plurality of oil passages side by side in a single unit. 30 Apparatus of preferred form and construction has been illustrated and described for the purpose of showing a way in which this invention may be used, but the inventive thought upon which the application is based, 35 is broader than this illustrated embodiment thereof, and I therefore intend no limitations other than those imposed by the appended claims.

I claim:

- 40 1. An improved apparatus for effecting a heat transfer between a relatively hot and a relatively cold fluid comprising a casing having separate inlets and separate outlets for the fluids, a plurality of passages leading 45 from one fluid inlet to the outlet, a plurality of passages juxtaposed transversely thereto and arranged alternately therewith and means in said last mentioned passages for breaking up the body of fluid as it is moved 50 therethrough, said means comprising a plurality of corrugated baffle plates mounted transversely of said latter passages and provided with perforations through which said fluid must pass in moving therethrough. 55 2. An improved apparatus for effecting a heat transfer between a relatively hot and a relatively cold fluid comprising a casing having separate inlets and separate outlets for the fluids, a plurality of passages leading 60 from one fluid inlet to the outlet which are arranged to conduct the fluid first in one direction then in another and a second plurality of passages juxtaposed transversely and arranged alternately with said first mentioned 65 passages so as to move the fluid transversely

and generally counter current to the other fluid, baffles in said second passages consisting of corrugated sheets having staggered perforations in the corrugations for breaking up the body of fluid as it is moved transversely 70 there thru.

3. A heat exchange device comprising a casing, means for passing fluid through said casing in a plurality of tortuous paths, means for passing a second fluid through said 75 casing comprising a plurality of passages arranged between said tortuous paths, and corrugated baffles arranged in said passages transversely to the direction of flow of said second fluid, the corrugations of said baffles 80 being provided with perforations through which said second fluid passes, said perforations serving to break up said second fluid in its path through said casing.

4. In fractional condensation apparatus, 85 means for passing relatively hot vapors in heat interchange relation with relatively cold liquid comprising a casing having separate inlets and separate outlets for the fluids, un- 90 obstructed passages leading from the liquid inlet to the outlet, adjacent vapor passages arranged alternately with said first mentioned passages, perforated plate baffles in said vapor passages for breaking up the streams of vapor as they are moved trans- 95 versely therethrough and means for withdrawing condensate from said vapor pas- sages.

In testimony whereof I have hereunto set 100 my hand this 7th day of October, 1930.

WILLIAM J. RYAN.
